(57) **CLAIM**

The ornamental design for a connector of a nasal cannula assembly, as shown and described.

DESCRIPTION

FIG. 1 is a perspective view of a connector for a nasal cannula assembly.

FIG. 2 is a rear view thereof.

FIG. 3 is a front view thereof.

FIG. 4 is a left side view thereof.

FIG. 5 is a right side view thereof.

FIG. 6 is a top view thereof; and,

FIG. 7 is a bottom view thereof.

The broken lines in the drawings illustrate portions of the nasal cannula assembly or portions of the connector for a nasal cannula assembly which form no part of the claimed design.

The references to “left,” “right,” “front,” “rear,” “top,” and “bottom” in the figure descriptions are not meant to require certain in-use orientation; the connector for the nasal cannula assembly according to the claim design may be used in any orientation.
